UNITED STATES PATENT OFFICE.

SAMUEL WARK, OF ORTING, WASHINGTON.

WASHING APPARATUS.

1,369,591.

Specification of Letters Patent. Patented Feb. 22, 1921.

Application filed January 22, 1919. Serial No. 272,559.

To all whom it may concern:

Be it known that I, SAMUEL WARK, a citizen of the United States, residing at Orting, in the county of Pierce and State of Washington, have invented new and useful Improvements in Washing Apparatus, of which the following is a specification.

My present invention pertains to washing machinery; and it contemplates the provision of a simple, easily constructed and efficient apparatus of the suction-plunger type, and one adapted to be operated with the expenditure of but little effort.

Other objects and practical advantages of the invention will be fully understood from the following description and claim, when the same are read in connection with the drawings, accompanying and forming part of this specification, in which—

Figure 1 is a side elevation of my novel apparatus complete.

Fig. 2 is a top plan view of the same.

Fig. 3 is an enlarged top plan view of the plunger *per se*.

Fig. 4 is a diametrical section of the plunger taken through the bail thereof.

Fig. 5 is a diametrical section taken in a plane at right angles to Fig. 4.

Fig. 6 is an inverted plan view of the plunger.

Similar numerals of reference designate corresponding parts in all of the views of the drawings.

My novel washing apparatus involves the use of a tub 1, which may be an ordinary wash tub, or any other receptacle of about the same diameter as a wash tub.

The said tub 1 is designed to be superimposed upon a support 2, which may be a bench or the like, and fixed to and rising from the support 2 is an upright 3, to the upper portion of which is pivotally connected one end of a long hand lever 4, the latter being arranged to be swung vertically in a plane above the center of the tub 1. In the preferred embodiment of my invention the lever 4 is provided above the tub with a longitudinal vertical slot 5.

Arranged to be reciprocated vertically in the tub 1 is the plunger 6, which constitutes the salient element of the apparatus. The said plunger 6 is characterized by a specific construction that is at once susceptible of production without the employment of expensive machinery, and is simple and free

from delicate parts such as are likely to get out of order after a short period of use. The said plunger comprises a circular wooden body 7 having a central vertical aperture 8, a metallic flange 9 fixed to and depending from the perimeter of the body 7, a bail 10 disposed diametrically above the body 7 and fixedly attached at its ends to said body, a vertical central shank 11 into which the bail merges at a point above the center aperture 8 of the body, a housing 12, of sheet metal, fixed upon the upper side of the body 7 and having its body wall 13 spaced above the wooden body 7 and provided with an aperture 14 that is registered with the aperture 8, and a vertically swinging clack valve 15, preferably of sheet metal, hingedly connected at one end to the top wall of the housing. The shank 11 of the plunger is disposed in the slot 5 of the hand lever 4 and is pivotally connected to said hand lever through the medium of a pintle 16 which extends through one of a plurality of apertures 17 in the shank; the plurality of apertures being provided for adjustment purposes.

In practice I contemplate making the plunger of such diameter that there is a clearance of approximately a half inch between the exterior of the plunger flange 9 and the inner side of the side wall of the tub 1.

In the practical operation of my improvement the lever 4 is oscillated by hand to move the plunger rectilinearly downwardly and upwardly in the tub. Incidental to the downward movement of the plunger the valve 15 will open so as to render the movement easy and so as to enable the flange 9 and the body 7 to crowd the mass of clothes in the tub and during the upward movement of the plunger the valve will close with the result that the plunger will exert upward suction calculated to violently draw the water and the detergent therein through the clothes with the result that the clothes will be quickly and thoroughly cleansed, and this without injury to the clothes, irrespective of the character thereof.

As shown by dotted lines in Fig. 5, the bail 10 serves the supplemental function of limiting the opening movement of the clack valve 15.

As will be apparent from the foregoing, the chief characteristics of my novel apparatus are simplicity and strength in construc-

tion, ease of operation, and capacity to quickly and thoroughly cleanse clothes with the expenditure of but a minimum amount of effort on the part of the operator.

5 Having described my invention, what I claim and desire to secure by Letters Patent, is:

A reciprocatory washing machine plunger, comprising a wooden body having a central 10 vertical aperture, a metallic flange fixed to and pendent from the perimeter of the body, a sheet-metal housing mounted upon the body and having a flange fixed to the body

and also having a central aperture above and registered with that in the body, a vertically-swinging flap valve mounted upon the body wall of the housing and connected at one end in hinged manner to said wall, and a transverse bail in a vertical plane parallel to and spaced from that of the hinge and straddling the housing above and attached to the upper side of the body and having vertical lapped and connected portions forming a shank. 15 20

In testimony whereof I affix my signature.

SAMUEL WARK.
